UNITED STATES PATENT OFFICE.

GARNET NELSON HUGHES, OF PICTON, ONTARIO, CANADA.

RECORD HOLDER FOR TALKING MACHINES.

1,402,614.

Specification of Letters Patent.

Patented Jan. 3, 1922.

Application filed September 25, 1920. Serial No. 412,774.

To all whom it may concern:

Be it known that I, GARNET NELSON HUGHES, a subject of the King of Great Britain, and resident of the town of Picton, in the Province of Ontario and Dominion of Canada, have invented certain new and useful Improvements in Record Holders for Talking Machines, of which the following is a specification.

10 This invention relates to improvements for record holders for talking machines.

The usual practise in filing records is to place each in a separate envelope and then place the envelopes in a cabinet, but such a system has many drawbacks, one of the greatest being the difficulty of re-locating a particular record or piece of music and, besides, this type of filing is open to the objection that dis-arrangement of the records will 20 always take place.

Another common practise is to file the records in folios or in albums but the difficulty of locating any particular record is also present in this case, although not so 25 prominently as in the above mentioned practise, and, besides, misplacing of records very frequently happens.

Another objection to the above system is that an abrasive action is usually set up between adjacent records both when extracting 30 the record and when replacing it in the cabinet and, as a consequence, the lifetime of the record is lessened.

The principal objects of the present invention are to provide a holder in which the 35 records can be filed away, each record having an individual compartment or space in which it will be housed and the walls or partitions of each compartment will be protected by a soft material which will have a 40 non-abrasive action on the records.

Further objects of the present invention are to provide ejecting means whereby the 45 records can be quickly extracted from the cabinet, the ejectors being so constructed that in the event of a record being removed the operating key of the ejector will be depressed thereby indicating the exact compartment to which the record should be returned.

Further objects still are to construct the 50 holder as a unit so that it may be positioned in cabinets at present in use and generally to adapt the holder to better perform the 55 functions required of it.

With the above and other objects in view

the invention consists essentially of the improved construction and arrangement of parts particularly described and set forth in the following specification and accompanying drawings forming part of the same.

In the drawings;

Figure 1 is a perspective view of a cabinet having my improved record holder installed therein.

Figure 2 is a vertical section through the cabinet showing the location of the record holder.

Figure 3 is a fragmentary perspective view of the record holder.

Figure 4 is a perspective view of the lower portion of the record holder.

Figure 5 is a transverse section of that portion illustrated in Figure 4 and showing the grooves covered by felt or a similar soft material.

Figure 6 is a perspective view of one of the ejector levers.

Figure 7 is a transverse section through the upper end of the lever showing the U shaped finger with the felt or other similar soft lining.

Fig. 8 is a perspective view of one of the rods which co-acts with one of the levers.

Figure 9 is a perspective view of a key which co-acts with one of the rods.

Figure 10 is a perspective view of the skeleton frame of the record holder.

Like characters of reference refer to like parts in the several figures.

Referring to the drawings;

A represents a cabinet in which my improved record holder B is mounted. The cabinet may be of any suitable size and shape but will be of a nature to permit of the record holder B being inserted therein as a complete unit and secured within the cabinet by a suitable means.

The record holder B comprises a skeleton frame consisting of side members 10 connected at the rear end to an inverted U shaped member 11 which is formed of uprights connected by a transverse member. This transverse member is provided with a plurality of equidistantly spaced and vertically disposed recesses, 12.

Adjacent to the rear end of each of the side members 10 a curvilinear projection 13 is provided and is formed with an orifice 14 therethrough, and at the front end of each of the side members 10 an angle shaped projection 15 is formed.

On the outer edge of the angle shaped projection 15 an angularly disposed key board 16 is provided which is secured to the side members 10 by any suitable means 5 and this key board is provided with a plurality of orifices 17 therethrough arranged in rows with the adjacent rows staggered relatively to each other.

On the front an inverted U shaped member 18 is provided, the lower ends of the parallel arms of which are attached by straps 19 to the angle shaped projections 15 and the key board 16 by screws or the like and the upper transverse member is provided on the under face with a plurality of recesses 20. This frame is formed with an angularly disposed bottom wall 21 which is provided with a plurality of the rearwardly extending grooves or recesses 22 and adjacent to the front edge and on the upper wall of this bottom, a recessed portion 23 is provided and formed with rearwardly extending grooves 24 which are staggered relatively to the grooves 22.

15 A plurality of vertically disposed partitions 25 in the form of strips of metal or the like are positioned in the front U shaped frame 18, the upper edges of the partitions engaging with the grooves or recesses 20 and 20 the lower edges engaging with the grooves 24. These partitions are covered with green baize, felt or other suitable soft material which will have a non abrasive action on the records.

25 Extending rearwardly from the partitions 25 are strips 27 of metal or like suitable material which have their rear ends engaged with the vertically disposed grooves or recesses 12 of the rear U shaped member 11.

40 These strips 27 are covered for the greater part of their length with baize 28 or other suitable soft material. The partitions 25 and strips 27 subdivide the interior of the cabinet into a plurality of compartments 45 each of which will accommodate a record. In each compartment, an ejector lever 29 is mounted and these levers are pivoted on a transversely extending rod 30 which passes through the orifices 14 in the curvilinear projections 13 of the side members 10.

50 The upper arm of the levers 29 is formed in the front face with a central groove 31 and at the upper end a U shaped member 32 embraces the lever and is provided with a lining of felt 33 or other soft material.

55 The lower arm of the levers 29 co-acts with rods 34 which are slidably mounted on the bottom 35 of the holder B and the rear end of these rods may, if desired, be rounded and upturned to co-act with the said levers.

60 The rods 34 are provided adjacent to their front ends with recesses 36 forming a tongue 37 and these recesses accommodate the bevelled point 38 of the keys 39 which are slid-

ably mounted in the orifices 17 of the key board 16.

65 Each key 39 has a pin 40 extending through its lower end and the pins engage with orifices 41 provided in the recesses 36 of their 70 coacting rods 34.

The heads 42 of the keys 39 will be enlarged to form finger pushes and each head will have a number or other symbol marked thereon.

75 When a cabinet equipped with a record holder of this description is in use and the doors of the cabinet are open, the spaced partitions 25 are visible and each compartment formed by the said partition can, if 80 necessary, house a record.

Assuming that the compartments are 85 filled and that a particular record is required, then the operator will push a particularly numbered key corresponding to the compartment housing the desired record. This key will move its co-acting rod 34 rearwardly and the rod will tilt the lever 29 about its pivotal point so that the longer arm of the lever will be thrust forwardly thereby allowing the record which is engaged by the groove 31 and the U shaped finger 32 being fed forwardly so that a portion of its periphery will project beyond the front edge 90 of the partitions 25.

95 The record may now be removed for playing purposes. While the record is out of the cabinet, the key will remain in a depressed position and will indicate the compartment to which the record should be returned. When the record is being returned, it is pushed into the desired compartment and the record, rolling rearwardly in the groove 22 will engage with the lever 29 and rotate the same backwardly so that the lower end 100 of the lever will move the rod 34 forwardly and thus press the key outwardly so indicating that the record is now in the desired position within the holder.

105 The holder is extremely simple in construction and the records will be protected at all times when housed therein.

110 It should be particularly noted that the rotation of the levers 29 is governed by the rods 34 in the front thereof and by the transversely extending stop member 44 secured to the bottom 35 of the holder B.

115 The holders may be made to suit any type of cabinet and could be constructed of stock size to suit existing record cabinets.

120 It will be observed that the rods 34 are formed with upturned inner ends which enable the rods to remain in contact with the ends of the levers 31 for a longer period than would be possible were the ends not upturned.

125 As many changes could be made in the above construction and many widely different embodiments of my invention within the scope of the claims, constructed with-

out departing from the spirit or scope thereof, it is intended that all matter contained in the accompanying specification and drawings shall be interpreted as illustrative and 5 not in a limiting sense.

What I claim as my invention is:—

1. A container for talking machine records comprising a cabinet, a holder within the cabinet having a frame formed with an angularly disposed bottom wall having a plurality of rearwardly extending grooves thereon adjacent to the front edge, a plurality of slideable rods mounted on the bottom of the cabinet and below the angularly disposed wall, an angularly disposed key board extending at an acute angle to the said bottom, a plurality of keys extending through the key board and adapted to engage the rods, a plurality of projections at 20 the rear of the cabinet, a plurality of levers

mounted on the projections having their lower ends adapted to be engaged by the aforesaid rods, and having their upper ends adapted to engage the records.

2. A holder for talking machine records comprising a cabinet having a plurality of compartments, a plurality of pivoted levers having lower free ends, a plurality of reciprocal rods having upwardly turned ends adapted to engage the free ends of the 30 levers, a plurality of keys adapted to engage the rods, and means on the levers adapted to engage the records.

In witness whereof I have hereunto set my hand in the presence of two witnesses. 35

GARNET NELSON HUGHES.
